UNITED STATES PATENT OFFICE.

TUFFIELD GEORGE, OF FORT FRANCES, ONTARIO, CANADA, ASSIGNOR OF ONE-HALF
TO PETER J. NOEL, OF FORT FRANCES, ONTARIO, CANADA.

WATER-HEATER.

1,100,236.

Specification of Letters Patent. Patented June 16, 1914.

Application filed October 16, 1913. Serial No. 795,586.

To all whom it may concern:

Be it known that I, TUFFIELD GEORGE, a citizen of the United States, residing at Fort Frances, in the Province of Ontario and Dominion of Canada, have invented 5 a new and useful Water-Heater, of which the following is a specification.

The device forming the subject matter of this application is adapted to be assembled 10 with a boiler wall and a boiler, for the purpose of doing away with the brick arch, and, at the same time providing a means whereby the water which is delivered to the boiler may be heated.

15 The invention aims to provide a novel means whereby a circulation of water through the heater will be secured, means being provided for caring for the steam generated in the heater.

20 It is within the scope of the invention to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the accompanying drawing:—

35 Figure 1 is a perspective showing the invention assembled, in duplicate form, with a boiler wall and a boiler; Fig. 2 is a longitudinal section of one casing; Fig. 3 is a transverse section of one casing; Fig. 4 is 40 a top plan of one casing, the lid thereof being removed.

In the accompanying drawing, the numeral 1 indicates a portion of a furnace wall, the numeral 2 indicating the grate and the 45 numeral 3 indicating the boiler.

In carrying out the invention there is provided 50 a casing C, the same comprising a body 4 of box-like form, the body having an upwardly arched bottom 5, at the ends of which flat supports 6 are located, the supports 6 resting upon the walls 1. Threaded studs 7 project upwardly from the body 4 and pass through a lid 8, nuts 9 being applied to the studs to hold the lid in place.

55 The upwardly arched bottom 5 is provided

with an opening 10, surrounded by a conduit 11 secured to or formed integrally with the bottom 5. The conduit 11 extends upwardly through the lid 8 and may be provided with an outstanding flange 12, engaged beneath the lid 8, the flange 12 being equipped with studs 14 which project through the lid, and nuts 15 being applied to the studs 14 to engage and hold in place the lid 8.

Extended longitudinally of the body portion 4 of the casing C is a partition 16, dividing the interior of the casing into a main compartment 17 and into an auxiliary compartment 18. The partition extends upwardly from the arched bottom 5 into contact with the lid 8, and in the upper edge of the partition, notches 19 are formed, adjacent the lid. These notches 19 serve to permit steam, should any be generated, to pass 70 from one compartment to the other, the lid 8 being equipped with a steam outlet 20.

In one end of the body 4 of the casing C there is a water inlet 21 and a water outlet 22. The water inlet 21 communicates with 80 the main compartment 17 and the water outlet communicates with the auxiliary compartment 18. An overflow pipe 28 enters the end of the casing adjacent the inlet 21 and the outlet 22. The notches 19 in the partition 16 are located above the overflow pipe 28. That end of the partition 16 which is remote from the water inlet 21 and the water outlet 22 is cut away from its lower edge as indicated at 23 to form an opening 90 85 24.

The practical operation of the structure is as follows:—Water is admitted to the main compartment 17 through the inlet 21. The water thence travels upwardly along 95 the arched bottom 5 in the compartment 17 and, passing through the opening 24 existing below the lower edge 23 of the partition 16, moves into the auxiliary compartment 18. Thence, the water travels upwardly along 100 the arched bottom 5, in the compartment 18 and passes away through the water outlet 22. It is within the scope of the invention to employ a plurality of the casings C, disposed one behind the other as shown in Fig. 105 1 and, under such circumstances, a pipe 25 forms a communication between the water outlet 22 of one casing and the water inlet 21 of an adjoining casing. From the water outlet 22 of the rearmost casing, a pipe 26 110

leads to the boiler and discharges the heated water thereinto. At times it may be desirable to duplicate the structure shown in Fig. 1, and under such circumstances the foremost casing C may be provided with a pipe 27 for the purpose of establishing a communication with another line of casings, duplicating the line shown in Fig. 1. Should steam be generated in either of the 10 compartments 17 or 18, the same will flow away through the steam outlet pipe 20, the notches 19 in the partition 16 serving to permit a free circulation of steam in the compartments. The overflow outlet 28 lies 15 below the notches 19 and thus the notches 19 will always remain open for the passage of steam.

The conduit 11 serves to permit liquid fuel to pass through the casing and into the 20 space above the grate 2. The conduit 11 serves not only to conduct this liquid fuel, but, as well, reinforces the casing in that it forms a communication between the arched bottom 5 and the lid 8. The rearmost casing 25 C may support the boiler 3. The side faces of the casings may be provided with locking ribs 50 adapted to engage with a row of mortised bricks.

The casings may be made of cast metal, 30 boiler iron or any other suitable substance.

Having thus described the invention, what is claimed is:—

1. In a device of the class described, a casing including a body having an upwardly arched bottom; a barrier extended transversely of the bottom and having an opening located below the crown of the bottom and to one side of the crown of the bottom; a water inlet for the casing and 35 located upon one side of the barrier and upon the other side of the crown of the bottom and below the crown of the bottom; and a water outlet for the casing located upon the other side of the barrier and 40 above the crown of the bottom.

2. In a device of the class described, a casing comprising a body and a lid; a partition in the casing and extended between the body and the lid, the partition dividing the 45 casing into a main compartment and an auxiliary compartment; a water inlet and a water outlet at one end of the casing, the inlet communicating with the main compartment and the outlet communicating with the auxiliary compartment; the partition having an opening located adjacent the other end of the casing; the casing being

provided with a water overflow and with a steam outlet, and the partition having a steam passage located above the overflow. 60

3. In a device of the class described, a casing including a body having an upwardly arched bottom, and a lid; a fuel conduit connecting the lid and the arched bottom and constituting a support for the arched 65 bottom and the lid; a partition connected with the arched bottom, the outer ends of the partition being connected with the casing and the inner ends of the partition being connected to the conduit and the partition having an opening located adjacent one end of the casing; and a water inlet and a water outlet entering the casing adjacent its other end.

4. In a device of the class described, a 75 plurality of separate individually removable casings; partitions in the casings and defining a main compartment and an auxiliary compartment in each casing; an external pipe forming a communication between 80 the auxiliary compartment of one casing and the main compartment of an adjacent casing; one casing having a water inlet communicating with the main compartment thereof and located upon the same end of 85 the casing as the communication, and the other casing having an outlet communicating with the auxiliary compartment thereof and located on the same end of said casing as the outlet of the first casing; the partitions having openings located adjacent their lower edges and disposed adjacent the ends of the casing which are remote from the communication and the inlet. 90

5. A device of the class described comprising a plurality of separate individually removable casing units; partitions in the units dividing each unit into a main compartment and an auxiliary compartment; a communication between the main compartment of one casing and the auxiliary compartment of an adjacent casing and external 95 to the casings; and means for admitting water into the main compartment of one unit and from the auxiliary compartment of 100 the other unit.

In testimony that I claim the foregoing as my own, I have hereto affixed my signature in the presence of two witnesses.

TUFFIELD GEORGE.
